United States Patent Office

Des. 191,179
Patented Aug. 22, 1961

191,179

CAN CRUSHER

Arthur R. Podolske, Milwaukee, Wis., assignor to Milwaukee Metal Products Company, Milwaukee, Wis., a corporation of Wisconsin

Filed Dec. 16, 1960, Ser. No. 63,239

Term of patent 14 years

(Cl. D55—1)

Fig. 1.

Fig. 2.

Fig. 4.

Fig. 3.

FIG. 1 is a perspective view of a can crusher showing my new design;

FIG. 2 is a top view in slight perspective;

FIG. 3 is a rear view in slight perspective; and

FIG. 4 is a perspective view of the right side thereof.

The dominant features of my design are shown in full lines.

I claim:

The ornamental design for a can crusher, substantially as shown and described.
